UNITED STATES PATENT OFFICE.

OSCAR S. SWANSON, OF JAMESTOWN, NEW YORK.

ELECTRICAL SWITCH.

1,411,131.

Specification of Letters Patent. Patented Mar. 28, 1922.

Application filed December 10, 1918. Serial No. 266,091.

To all whom it may concern:

Be it known that I, OSCAR S. SWANSON, a citizen of the United States, residing at Jamestown, in the county of Chautauqua and State of New York, have invented new and useful Improvements in Electrical Switches, of which the following is a specification.

My present invention pertains to electrical switches; and it contemplates the provision of an electrical switch that is simple and inexpensive in construction, reliable, well adapted to withstand the usage to which electrical switches are ordinarily subjected, and calculated to lend itself to use in lamp sockets and many other applications.

The switch constructed in accordance with my invention is also, by reason of its characteristics, adapted to practically eliminate fire danger; and, with the foregoing in mind, the invention consists in the peculiar construction, novel combinations and adaptation of parts as hereinafter described and explicitly claimed.

In the accompanying drawings, hereby made a part hereof:

Figures 1 and 2 are elevations of opposite sides of a lamp socket embodying my novel switch.

Figure 3 is an enlarged vertical section showing the elements of the switch.

Figure 4 is a section on the line 4—4 of Figure 3.

Figure 5 comprises perspectives of elements that enter into the switch.

Figures 6 to 9 are views of a modified embodiment of my invention.

Referring by numeral to the said drawings and more particularly to Figures 1 to 5 thereof:

1 is a threaded lamp socket, and 2 is the body thereof; said body being formed in two semi-circular sections, Figure 4, to one of which the socket 1 is suitably attached and preferably in a permanent manner. The said sections are formed of suitable insulating material, and in the preferred embodiment one is provided with a key 3 and the other with a complementary depression 4, so that the two sections may be accurately registered incidental to assembling. It will also be apparent that the complementary key and depression will assist in holding the sections together in proper working relation.

In Figures 1 and 2 are shown the wire connections 5 and 6 to the switch and socket,

and by comparison of Figures 1 to 4 it will be readily understood that the current will pass from one pole of a source of energy to a binding screw 7, and then through a conductive plate 8, through a bolt 9, a ratchet disc 10, a contact member 11 and a terminal 12 thereon to the center contact of an incandescent lamp (not shown). From the filament of the lamp the current will pass through the socket 1, a screw 13, a conductive plate 14, and a binding screw 15 back to the opposite pole of the source of energy. From this it will be manifest that with the disc 10 in contact with the element 11 current will course through the filament of the lamp to cause said filament to glow. When, however, the disc 10 is not in contact with the element 11 no current will be supplied to the filament.

I denominate the element 10 a ratchet disc because it is provided at one side with spaced radial abutments 16. Said disc, however, is also provided with spaced contact arms 17, which form important parts of my invention. Retrograde rotation of the disc 10 is effectually prevented by a pawl 18, Figures 3 and 5, which cooperates, as will be readily understood, with the said abutments 16, and is adapted to yield and permit of rotation of the disc 10 in a clockwise direction. The contact arms 17 of the disc are provided with beveled forward portions 19, Figures 4 and 5, this provision being made to facilitate the passage of the said arms 17 between the spaced and more or less resilient and flared shoes 20 on the contact member 11.

Mounted to swing on the bolt 9 is a lever 21, having a handle 22. Adjacent to the center of movement the said lever 21 is provided with detents 23, so positioned that they will simultaneously engage abutments 16 on the disc 10 in order to transmit positive motion from the lever 21 to the disc. On the return forward movement of the lever 21, however, the detent 23 will ride idly against the side of the ratchet disc. A spring 24 is coiled about the bolt 9, Figures 3 and 4, and has a terminal arm 25 in engagement with the lever 21, and a terminal arm 26, connected with the body, preferably in the manner shown in Figure 3—i. e., by having a hook end that straddles a lateral lug 27 on the pawl 18, as best shown in Figure 3. The said spring is put under tension by depression of the lever 21, and it serves

not only to return said lever to the position shown in Figures 2 and 3, but also to yieldingly maintain the lever in said position. It will also be appreciated here that the coiled portion of the spring serves the additional function of yieldingly pressing the detent portion of the lever 21 against the ratchet disc, and in that way contributes to the reliability in operation of the combination.

10 As best shown in Figures 2 and 4, the bolt 9 is effectually insulated from the conductive plate 14 through the medium of an insulating washer 30.

15 It will be readily apparent from the foregoing that when the lever 21 is depressed and the disc 10 is thereby turned through a part of a revolution, one of the contact arms 17 of the disc will be positioned between the shoes 20 of the contact member 11, and, 20 in consequence, the electrical current will be supplied to the lamp as before specifically pointed out. When the disc 10 is turned, as stated, the pawl 18 will spring into engagement with the first abutment 16 25 that is presented to its free end, and the attendant click will apprise the operator of the fact that the connection has been made. Likewise when the lever 21 is subsequently depressed to interrupt the supply of current to the lamp, the click attending the new engagement of the pawl 18 will inform the operator that the current is cut off. Following each depression of the lever 21 30 and the release of said lever the spring 24 will operate to promptly return the lever to the normal position shown in Figures 2 and 3.

35 It is believed that my novel switch will be readily understood from the foregoing, and it is also thought that in the light of such description the practical utility of the switch will be readily apparent.

In the embodiment shown in Figures 6 to 9 the pintle 9^w serves to support the sleeve 9^w which turns about the pintle and back of the cap 2^u, and is equipped in rear of the cap with a disc 20^u, which bears on its face letters, words as shown, or other means calculated to visually indicate when the switch is on or in condition to establish circuit through the switch and when it is off or in position to interrupt the circuit through the switch. It will be observed in this construction that the disc 10^u on sleeve 9^w carries arms 10^w to make contact with terminals or contact members 11^v, and is also provided with abutments 12^w for the engagement of detents 13^w on the lever 14^w which is mounted to swing about the sleeve 55 which is subject to the action of a spring 15^w having the two-fold capacity of function ascribed to the spring in the other embodiment.

The operation of the last mentioned embodiment will be fully appreciated when it

is stated that when the arms of the disc 10^u are in contact with the terminals 11^v the disc in rear of the closure cap 2^u will indicate that the switch is in position to complete the circuit, while when said arms 70 of the disc are out of contact with the terminals 11^v the disc will indicate the interruption in the circuit.

It will be apparent from the foregoing that in both of the embodiments of my invention the working parts of the switch are carried by a body of insulating material, and a closure means consisting of another body of insulating material or any other closure device, such as a cap, Figures 6 to 9, is suitably connected to the first-named body of insulating material with a view to covering and protecting the working parts of the switch.

It will also be apparent that in both of the embodiments shown and described, the circuit is established and is interrupted by the step by step movement of a revoluble disc. From this it follows that each of the embodiments is possessed of the advantage 80 of simplicity in construction, coupled with reliability in operation, and this without the danger of fire being caused by the switch.

By reference to Figure 1 it will be noticed that a lateral projection 60 is provided on one section of the insulating body 2. This projection 60 serves to rest in the slots or grooves provided in the insulating material and a socket shell (not shown), 100 with a view to preventing the hand lever of my novel switch from binding in the slot that is also provided in the said socket shell and the insulating lining thereof.

By comparison of Figures 7 to 9 it will be observed that a porcelain segment 14^x, connected by bolts as shown, is employed to close the slot in which the inner end of the lever handle is arranged to play.

Having described my invention, what I claim and desire to secure by Letters Patent, is:

The combination in an electrical switch, of a dielectric body, a yieldable terminal connected with said body, a revoluble disk 115 arranged in and connected with the body and having spaced arms arranged to wipe past and contact with said terminal and also having spaced abutments immediately back of said arms, yieldable means connected with the body to cooperate with said abutments and prevent retrograde rotation of the disk, and a lever connected with the body and extending from the same and having a detent arranged on movement of the 120 lever in one direction to cooperate with said abutments in the step by step rotation of the disk.

In testimony whereof I affix my signature.
OSCAR S. SWANSON.
